WOOD SIDING CONSTRUCTION

Gerald A. Koenighof, Kensington, Md., assignor to
Timber Engineering Company, District of Columbia, a
corporation of Delaware

Filed Mar. 6, 1963, Ser. No. 263,150

5 Claims. (Cl. 52—465)

This invention relates to wood siding construction and more particularly, to means for forming a butt joint between pieces of lap siding.

In conventional building construction, lap siding is applied to an outside wall in successive courses from the ground upward. Each course of siding overlaps the preceding course. Often the siding is not sufficiently long to span the entire length of the wall and it is necessary to form a butt joint between two pieces of siding in the same course. If the adjacent ends of the siding are cut square and the exposed surfaces of the siding are flat, then a reasonably tight joint can be formed. Since the siding has a substantially greater width than thickness, however, there is a tendency for the siding to warp or cup transversely. Depending on the grain structure of the siding, it may cup either outwardly or inwardly. If one of the pieces of siding is cupped outwardly, or convexly, and the other piece of siding is cupped inwardly or concavely, there will be a discontinuity between the pieces of siding at the joint. If the butt joint between the lap siding is not tight, water may leak into the space between the siding and the sheathing and cause rotting of the siding and blistering of the paint on the siding.

When the lap siding is cut crosswise to form the joint, splinters may be pulled from the exposed surface of the siding by the saw and the abutting edges may be rough. Also, the saw cut may not be square and there may be a slight gap in the joint. To overcome these deficiencies, caulking has been applied over the butt joint to seal against the entry of moisture. Since manual labor is required to apply the caulking or filler, this method of sealing the joint is relatively expensive and the joint may still be unsightly due to the rough surface of the filler, or due to the discontinuity between oppositely cupped pieces of siding.

In view of the defects of the prior art methods of forming a butt joint in lap siding, it is an object of this invention to provide an improved means for sealing the butt joint in lap siding.

It is a further object of this invention to provide a lap joint sealing means which is easily applied.

It is another object of this invention to provide a butt joint sealing means which is inexpensive and has an attractive appearance.

These objects are accomplished in accordance with a preferred embodiment of the invention by an elongated strip which is both transversely and longitudinally curved. At their abutting edges, the surfaces of the siding are drawn into coplaner relation by a nail or other fastener which is driven into the joint between the abutting lap siding, so that a portion of the fastener engages both pieces of siding. One end of the strip is formed with a tab projecting on the side of the strip which has a convex longitudinal curvature. The transverse curvature of the strip is convex on the side opposite the tab. The tab forms a socket for engaging over the lower edge of a piece of lap siding and the opposite end of the strip is secured to the upper edge of the siding by a nail or other suitable fastener. Thus, the cover of this invention spans the joint and due to the spring pressure in the metal, fits closely against the face of the siding, so that water or moisture does not seep under the cover. The next succeeding course of siding overlaps the upper edge of the

2

siding and the cover strip, so that the nail or fastener in the strip is not exposed.

This preferred embodiment of the invention is illustrated in the accompanying drawings in which:

5 FIG. 1 is a side elevational view of a wall with bevel siding having a butt joint over which the cover of this invention is applied;

FIG. 2 is a cross sectional view, partly schematic along the line 2—2 in FIG. 1;

10 FIG. 3 is a cross sectional view along the line 3—3 in FIG. 2;

FIG. 4 is a side elevational view of the butt joint cover of this invention;

15 FIG. 5 is a top plan view of the cover;

FIG. 6 is a cross sectional view of the cover along the line 6—6 in FIG. 4; and

20 FIG. 7 is a cross sectional view of the cover along the line 7—7 in FIG. 4.

Conventional lap siding is applied to a wall of a building over sheathing or other wall structure 2 and vapor barrier material 4. The siding may be any of a variety of shapes and sizes and may be beveled, or it may have a uniform thickness. A lower piece of siding 6 is secured to the sheathing 2 by nails, or other suitable means.

25 An intermediate course of siding is formed of two separate pieces of siding 8 and 10 with the abutting ends of the pieces of siding 8 and 10 forming a joint 12. An upper course of siding 14 is applied to the sheathing 2 and overlaps the upper edge of the siding 8 and 10.

30 The joint cover of this invention is applied over the joint 12 before the upper course of siding 14 is secured to the wall 2. The cover 16 is formed of a strip of a resiliently flexible material, such as metal, and is provided at one end with a tab 18 which forms a socket for engaging over the lower edge of the siding 8 and 10. The strip 16 is curved longitudinally in an arc having a center of curvature on the opposite side of the strip from the tab 18. The strip is also curved transversely in an arc having a center of curvature on the same side of the strip as the tab 18, as shown in FIG. 6. The upper end of the strip 16 is secured to the wall 2 by a nail or other fastener 20 which extends through the strip 16, the siding, and into the wall.

35 In order to draw the pieces of siding 8 and 10 together, so that their surfaces lie substantially in the same plane, a nail 22 is preferably applied in the joint 12. The head of the nail engages the surface of both of the pieces of siding 8 and 10, as shown in FIG. 3. Since the strip 16 is curved, the outer longitudinal edges of the strip engage the surface of the siding 8 and 10 tightly and span the joint 12, without interference from the head of the nail 22. The transverse curvature of the strip 16 not only provides space for the head of the nail 22, but it also increases the flexural strength of the strip. Furthermore, the longitudinal edges of the strip 16 engage the surfaces of the siding 8 and 10 at an acute angle with the surface, so that the maximum pressure is applied at the junction of the metal strip 16 and the surface of the siding to form a tight seal.

40 The strip 16 is curved longitudinally to facilitate application of the strip to the siding and to apply the maximum pressure along the edges of the strip to form a tight seal between the strip and the surface of the siding 8 and 10. The preformed curvature imposes a bending stress 45 in the strip which urges the lower portion of the strip, as shown in FIGS. 1 and 2, away from the exposed surface of the siding, but the tab 18 overlaps the interior surface of the siding and the strip 16 is urged tightly against the surface. The upper end of the strip 16 is secured by the nail 20 and the upper course of siding 14 protects the fastener or nail 20 from the weather.

45 50 55 60 65 70 75 80 85 90 95

The cover strip 16 is applied during the construction

of the wall by forming the butt joint 12 between adjacent pieces of siding 8 and 10 and, if desired, a nail 22 is inserted into the joint 12 to prevent cupping of the siding. The strip is secured over the joint 12 by inserting the tab 18 in the space between the siding 8 and 10 and the lower siding 6. The upper end of the curved strip 16 is then pressed against the surface of siding over the joint 12 and a nail 20 is driven into the sheathing to hold the strip in place. The upper course of siding 14 is then applied to overlap the upper edge of the siding 8 and 10 and to cover the nail 20. Moisture may accumulate under the cover due to wicking or the penetration of moisture from the inside of the wall. Accordingly, a drain hole 24, as shown in FIG. 7, is provided in the portion of the cover 16 which extends across the edge of the siding. The drain hole 24 permits any accumulation of moisture to be evaporated and thereby prevents rotting of the wood under the butt joint cover 16.

In the event that the siding has already been applied, the cover strip of this invention can be applied in substantially the same manner as described above. The strip 16 is inserted between the upper course of siding 14 and the siding 8 and 10 and the tab 18 is inserted between the siding 8 and 10 and the lower piece of siding 6. The lower end of the strip 16 is retained in position by the tab 18 which overlaps the lower edge of the siding 8 and 10 and the upper end is secured between the siding 8 and 10 and the siding 14. If the gap between the upper piece of siding 14 and the siding 8 and 10 is so large that the strip 16 does not tightly engage the surface of the siding 8 and 10 throughout the entire length of the strip, a nail may be driven through the upper piece of siding 14 directly over the strip 16 to secure the strip in position. Since the head of the nail will be exposed to the weather, however, it is necessary to set the nail head and cover it with a protective coating, such as paint.

The butt joint cover of this invention is formed of a single strip of metal and is therefore inexpensive. It may be easily applied by unskilled labor. Furthermore, since there are no fasteners exposed for securing the strip to the siding, there is no danger of leakage of water through the metal strip. The flexibility of the curved elastic strip urges the cover tightly against the surface of the siding, so that the strip is inconspicuous and forms a tight joint which excludes moisture from the interior of the wall.

While this invention has been illustrated and described in one embodiment, it is recognized that variations and changes may be made therein without departing from the invention as set forth in the claims.

I claim:

1. In combination a covered lap siding butt joint formed between coplanar abutting pieces of wood siding comprising a thin strip extending transversely across one face of the siding over the joint, one end of said strip extending across one edge of the siding and overlapping the opposite face of the siding, said strip being transversely curved with opposite longitudinal edges of said strip engaging said one face of siding, said strip being resiliently biased toward being curved longitudinally, and means for securing the opposite end of the strip to the siding whereby the intermediate portion of the strip is urged against the siding by the resilient longitudinal curvature of the strip.

2. In combination a covered lap siding butt joint formed between abutting pieces of wood siding com-

5 prising a strip extending transversely across one face of the siding over the joint, one end of said strip extending across one edge of the siding and transversely along the opposite face of the siding, a nail extending through the joint and overlapping said pieces of siding thereby drawing the faces of the siding into substantially the same plane, said strip being transversely curved to cover the nail and engage the faces of the siding along the edges of the strip and a second nail extending through the opposite end of the strip and the siding to secure the strip thereto.

10 3. In combination a covered lap siding butt joint formed between coplanar abutting pieces of wood siding comprising a thin strip extending transversely across one face of the siding over the joint, one end of said strip extending across one edge of the siding and overlapping the opposite face of the siding, said strip having opposite longitudinal edges and a central portion transversely arched outwardly between said edges and extending from said one end continuously for substantially the length of said strip, said edges engaging said one face of siding, said strip being resiliently biased toward being curved longitudinally, and means for securing the opposite end of the strip to the siding whereby the edges of the strip are urged against the siding by the resilient longitudinal curvature of the strip.

15 4. The combination according to claim 3, wherein said strip is metallic.

20 5. A lap siding butt joint cover comprising an elongated narrow strip having a front side and a rear side, opposite longitudinal edges and a central portion therebetween, said strip being of substantially uniform thickness, said strip having a socket formed at one end thereof, said socket including a spacer portion extending outwardly on said rear side of the strip and a tab portion extending from the spacer portion toward the opposite end of the strip, said strip being transversely arched continuously substantially from said socket to said opposite end with said opposite edges projecting in outwardly sloping relation on said rear side from said central portion, said strip having a continuous longitudinal curvature substantially from the socket to the opposite end of the strip with said longitudinal curvature being concave on said front side, said strip being sufficiently resilient to return to said longitudinal curvature when straightened, whereby said opposite edges are pressed tightly against the siding due to spring pressure in the strip when the cover is applied over a joint.
